UNITED STATES PATENT OFFICE.

RICHARD WUNNING, OF NEW YORK, N. Y.

SAFETY ELEVATOR ATTACHMENT.

1,209,099.

Specification of Letters Patent.

Patented Dec. 19, 1916.

Application filed August 30, 1915. Serial No. 48,091.

To all whom it may concern:

Be it known that I, RICHARD WUNNING, a citizen of the United States, and residing at New York, in the county of New York and State of New York, have invented certain new and useful Improvements in Safety Elevator Attachments, of which the following is a specification, such as will enable those skilled in the art to which it appertains 10 to make and use the same.

This invention relates to elevators, and particularly to passenger elevators, and the object thereof is to provide a device of this class with a simple and efficient attachment 15 to prevent the serious and sometimes fatal accidents, which result from the breaking of the hoisting cable or apparatus and the drop of the car to the bottom of the elevator shaft; a further object being to provide a 20 safety elevator apparatus or attachment which will also operate to stop the descent of the elevator car at a predetermined point or at any floor of the building in which the car may be operated; a still further object 25 being to provide a safety elevator attachment for elevator cars, of the class specified, with means which may also be operated to stop the descent of the car at any particular point in the shaft in which the car is used; 30 and with these and other objects in view, the invention consists in an apparatus of the class specified, constructed and operating as hereinafter described and claimed.

The invention is fully disclosed in the following specification, of which the accompanying drawings, form a part, in which the separate parts of my improvement are designated by suitable reference characters in each of the views, and in which:—

40 Figure 1 is a sectional view showing the bottom of an elevator car and my improved apparatus applied thereto and indicating the method of its operation; Fig. 2 a partial section on the line 3—3 of Fig. 1; Fig. 3 a 45 view similar to Fig. 1 but showing the parts in a different position; Fig. 4 a view similar to Fig. 2 but showing a modification and on the line 4—4 of Fig. 5; Fig. 5 a side view of the construction shown in Fig. 4; Fig. 6 a 50 view similar to Fig. 4, but showing another modification; Fig. 7 a side view of the construction shown in Fig. 6 with part of said construction shown in section; Fig. 8 a view similar to Fig. 1 but showing only part of the construction and showing a modification; Fig. 9 a view similar to Fig. 8 but

showing the parts in a different position, and Fig. 10 a view similar to Fig. 1, but showing only part of the construction and showing a modification.

In the drawing forming part of this specification, I have shown at *a* the bottom of an elevator car which is movable in a vertical shaft in the usual manner and at the opposite sides of which are vertical brake or 60 stop rails *a*² and these rails are preferably of T-form in cross section and may form a part of the guide rails between which the car is movable.

The elevator car or the bottom thereof is 70 provided with a hanging frame *a*³ of any suitable construction and provided with a horizontal base member *a*⁴ and mounted vertically in the frame *a*³ and centrally of the car is a threaded shaft *b* the top end 75 portion of which is provided with a reduced extension *b*² having a bearing in the bottom of the car and above which is an angular head *b*³ to which a wrench may be applied to turn said shaft as hereinafter described. 80

The shaft *b* is also provided at its lower end with a reduced portion *b*⁴ having a suitable bearing *b*⁵ in the bottom *a*⁴ of the frame *a*³, and the upper part *b*⁶ of the reduced lower end extension of the shaft *b* is an- 85 gular in form and mounted thereon is a clutch member *b*⁷ provided with a conical top *b*⁸ and a cylindrical bottom clutch hub *b*⁹.

Mounted on the bottom extension of the shaft *b* and in a horizontal position is a 90 beveled gear wheel *c* having a clutch hub member *c*² which operates in connection with the clutch hub member *b*⁹ and at one side of the frame *a*³ is mounted a horizontal shaft *c*³ having at its inner end a beveled gear *c*⁴ 95 which meshes with the gear *c*, and which is provided at its outer end with a gear *c*⁵ which meshes with a vertical rack bar *c*⁶ at one side of the elevator shaft and supported in any desired manner, and the shaft *c*³ is prefer- 100 ably supported by hangers *c*⁷ connected with the car or the floor thereof.

The governor shaft *d* is mounted in one side portion of the frame *a*³ opposite the shaft *c*³, and the upper end thereof is pro- 105 vided with a bearing in the floor of the car at *d*², and on the lower end thereof is mounted a horizontal gear *d*³ which meshes with a gear *d*¹⁰ mounted under the gear *c*, and the gear *d*³ is provided on the lower side thereof with a hub *d*⁴ having a bearing in the bottom of the frame *a*³, and said gear is also 110

provided on the top thereof with a clutch hub member d^5 .

The central portion d^6 of the shaft d is angular in form and is provided with a clutch member d^7 which operates in connection with the clutch member d^5 , and said shaft d is also provided with a governor d^8 of the usual form and involving a vertically movable sleeve or collar d^9 mounted on the 10 angular part d^6 of the shaft d .

The frame a^3 involves a horizontal portion a^5 on which is rotatably mounted a disk e with which is connected a link e^2 which is also connected with the sleeve or collar d^9 of 15 the governor d^8 , and connected with the top portion of the disk e is a slotted arm e^3 and connected with the lower inner portion of the disk e is a slotted arm e^4 , and pins or similar devices e^5 are passed through the slots in the 20 arms e^3 and e^4 and into the part a^5 of the frame a^3 , and the inner ends of the arms e^3 and e^4 are provided with heads e^6 which are preferably forked and which are supported 25 in a horizontal position and which operate in connection with the clutch member b^7 as hereinafter described.

Mounted on the threaded shaft b is a nut-shaped collar or block f to which are pivoted brake arms f^2 , said arms being provided at 30 their inner ends with fork-shaped heads f^3 which inclose the collar or block f and said arms are also supported by supplemental arms f^4 pivoted to or in the bottom a of the car, and the arms f^2 are forked at their outer 35 ends so as to engage the web members of the vertical brake or stop rails a^2 as shown at f^5 .

The operation of this construction will be readily understood from the foregoing description, and when taken in connection with 40 the accompanying drawing and the following statement: The position of the parts shown in Fig. 1 is the normal position, and in this position, the head of the arm e^4 is under the beveled head b^8 of the clutch member b^7 and said clutch member is held above and out of engagement with the clutch member c^2 . In the downward movement of the car, under normal conditions, the shaft c^3 will be rotated and this shaft will rotate the 45 gear d^3 and the shaft d and its governor will also be rotated, by the clutch member d^7 , which engages the clutch member d^5 . This operation of these parts will continue unless the elevator cable or apparatus used for raising and lowering the elevator fails and breaks, in which event the car would start downward much more rapidly than under 50 normal condition, and this would increase the speed of the governor d^8 , and the disk e would be turned so as to withdraw the head of the arm e^4 from beneath the head of the clutch member b^7 , and said clutch member b^7 would drop into engagement with the clutch member c^2 , and in this operation 55 the head e^6 of the arm e^3 aids in forcing the

clutch member b^7 downwardly. This operation will also result in rotating the shaft b and the collar or block f will be lowered on said shaft and the inner ends of the brake arms f^2 will be forced downwardly and the outer ends thereof outwardly and into close contact or engagement with the rails a^2 , and this operation will stop the descent of the car as will be readily understood, and this position of the parts is clearly indicated in Fig. 2, and the parts of the apparatus may be reset or returned to the normal position as shown in Fig. 1 as hereinafter described.

In Figs. 4 and 5 I have shown a modified form of the brake arms f^2 , or rather of the means by which said arms engage the brake rails a^2 , and in this form of construction the bottom of the car is provided with hanger rods g on which are mounted, and vertically movable with the car, clamping jaws g^2 , consisting of separate parts connected by the rods g . The jaws g^2 are adapted at their outer ends to engage the webs of the brake rails a^2 as shown at g^3 , and the arms f^2 are pivoted on horizontal rods g^4 supported beneath the car in any manner, and the outer ends of said arms are free and tapered and curved downwardly as shown at g^5 , and said ends operate between the inner under portions g^6 of the jaws g^2 , as clearly indicated in Fig. 4, and if the hoisting cable or apparatus should break at any time and the car drop or fall, the inner ends of the arms f^2 will be moved downwardly and the outer ends upwardly and laterally and the jaws g^2 would be caused to grasp and hold the rails a^2 and the descent of the car will be stopped as will be readily understood.

In the construction shown in Fig. 7, I substitute for the screw shaft b a plain shaft h , the lower end portion h^2 of which is angular in form the same as the threaded shaft b . Secured on the top portion of the shaft h is a beveled gear h^3 and the shaft h passes through a frame member h^4 supported beneath the car and in place of the brake arms f^2 , I employ two brake shafts h^5 , provided at their inner ends with bearings in the frame member h^4 , and with beveled gears h^6 which mesh with the gear h^3 , and the outer end portions of the shafts h^5 are provided with horizontally movable wedge members h^7 which are movable in keepers h^8 supported beneath the bottom of the car in any way, and the wedge members h^7 are provided with threaded bores and the outer ends of the shafts h^5 are threaded into said bores. With this construction, the downward drop of the car in case of the breakage of the hoisting cable or apparatus will rapidly rotate the shaft h in the same manner as shaft b with the construction shown in Figs. 1 and 2, and this operation will rotate the shafts h^5 , and the wedge members h^7 will be forced outwardly between the inner ends 130

of the jaws g^2 as indicated in Fig. 6, and the car will be brought to a stop, as will be readily understood.

In Figs. 8 and 9 I have shown means for

- 5 stopping a car at or about a floor level instead of midway between floor levels, and this means is employed in connection with the parts shown in Figs. 1 and 2, but may be employed in connection with any kind or 10 class of brake arms such as are shown in Figs. 1 to 3, or in Figs. 4 to 7, inclusive. In Figs. 8 and 9 I have shown at i a vertical guide at one side of the elevator shaft, and this guide may be of any kind or class and 15 may be one of the guides for the elevator car. The guide i is provided preferably adjacent to each floor of the building with an inwardly directed lug, projection or shoulder i^2 , and supported in hangers i^3 , 20 suspended beneath the bottom of the car as a horizontally movable bar i^4 provided at its outer end with a roller i^5 adapted to bear on the guide i , and to the inner end of which is pivoted at i^6 an L-shaped arm i^7 25 which is pivoted to a hanger i^3 at i^8 and the lower or shorter end of the L-shaped arm i^7 is provided with a head i^9 which is preferably forked and which is adapted to engage the clutch member b^7 and to fit under the 30 conical head thereof as clearly shown in Fig. 8. A bell crank j is pivoted to one of the hangers i^3 at j^2 and one end thereof is slotted and a pin j^4 is passed therethrough into the bar i^4 , and suspended from the 35 other end of the bell crank j is a weight j^5 , which normally serves to hold the bar i^4 and the arm i^7 in the position shown in Fig. 8, and as long as these parts are in the position shown in said figure the clutch members 40 or devices b^7 and c^2 cannot operate as hereinbefore described, and the descent of the car cannot be stopped even though the governor d^8 may already have withdrawn the arm e^4 from its operative position as shown 45 in Fig. 2, but as soon as the car reaches the lug, shoulder or projection i^2 , the bar i^4 and its connected parts will be thrown into the position shown in Fig. 9, in which position the clutch member b^7 is released and engages the clutch member c^2 , and from this 50 position the parts may be returned to the position shown in Fig. 8 after the breakage has been repaired by simply returning the clutch member and governor to their normal 55 position as shown in Fig. 1, as well as the brake arms f^2 , and the descent of the car will return the bar i^4 to the position shown in Fig. 8 as will be readily understood.

The construction shown in Fig. 10 is intended as a supplemental stop for the car in case the mechanism shown in Figs. 1 to 2 inclusive, or any part thereof should break under great strain, and in this form of construction I provide horizontal bars k at the 60 opposite sides of the elevator shaft or said

beams may form a part of said shaft, or the framework thereof and any desired number of said beams may be employed, and be regularly spaced between the top and bottom of said shaft. In this form of construction I provide the bottom a of the car with hangers k^2 in which are mounted horizontally movable bars k^3 the inner ends of which are provided with links k^4 which are pivoted to the nut-shaped collar or block f , 70 or the fork-shaped heads f^3 of the brake arms f^2 and the outer ends of the bars k^3 are adapted to operate in connection with or bear on the beams k as indicated in dotted lines. In the normal position of these 75 parts as shown in full lines, the bars do not engage the beams k , but if in the operation of the parts herein shown and described in checking the descent of the car, any part of 80 said parts should break after the governor has completed its operation, or when said 85 parts are under their greatest strain, the bars k^3 which have already been projected, will act as a stop for said car, or in other words, the bars k^3 are projected at all times 90 in the operation of the safety attachment as will be readily understood, but said bars will not act as stops unless the brake arms f^2 should fail to stop the car in its downward movement due to the breakage of said 95 bars or parts connected therewith. In order to reset the parts of the brake apparatus after they have been thrown into the position shown in Fig. 2 as hereinbefore described, all that is necessary is to return the 100 clutch member b^7 to the position shown in Fig. 1 after which a wrench can be applied to the head b^3 of the shaft b and turn it to the right. This operation will raise the block or collar f and the inner ends of the 105 brake arms f^2 and release the pressure of said arms f^2 on the brake rails a^2 as will be understood.

The construction shown in Fig. 10 may be used to support the car before the safety device is reset, should the break which causes the sudden descent of the car be so serious that the repairing thereof would take considerable time and this can be accomplished by turning the shaft b to the right enough to permit the car to descend slightly until the bars k^3 reach the first beams k at which point the car may be supported for any length of time without any strain on the various parts of my safety device.

While I have shown and described the preferred construction of the various details of my improvement, it will be apparent that my invention is not limited thereto, and changes therein and modifications thereof 115 may be made, within the scope of the appended claims, without departing from the spirit of my invention or sacrificing its advantages.

Having fully described my invention, 120

what I claim as new and desire to secure by Letters Patent, is:—

1. A safety attachment for elevator cars comprising a hanger frame connected with the bottom of the car, a vertical and rotatable main shaft mounted therein, a vertical rack bar at one side of the shaft, a horizontal shaft supported beneath the car and provided at its outer end with a gear which meshes with said rack bar and at its inner end with a beveled gear, a beveled gear rotatably mounted on the bottom part of the main shaft and meshing with the last named beveled gear and provided on its top surface with a clutch member, a supplemental clutch member vertically movable on the main shaft, and adapted to operate in connection with the clutch member on said gear, a vertical governor shaft, a gear rotatably mounted on the lower end portion thereof, a corresponding gear on the main shaft and adapted to mesh with said last named gear and provided on its top surface with a clutch member, a supplemental clutch member vertically movable on the governor shaft and adapted to operate in connection with the clutch member on the last named gear, a governor device mounted on the governor shaft and comprising a vertically movable part, a rotary device mounted between the governor shaft and the main shaft and in operative connection with said vertically movable part, clutch member controlling devices mounted between the rotary device and the main shaft and in operative connection with the rotary device and having a horizontal movement and adapted to operate in connection with the clutch member mounted on the main shaft, vertically arranged brake rails and radially arranged brake members adapted to be operated by the main shaft and operating in connection with said vertically arranged brake rails at the opposite sides of the elevator shaft.
2. A safety attachment for elevator cars comprising a hanger frame suspended beneath the car, a vertically arranged rack bar at one side of the elevator shaft, vertically arranged brake rails at the opposite sides of the elevator shaft, a main central shaft rotatably and vertically mounted in said frame, radially arranged brake devices in operative connection with said shaft and operating in connection with said brake rails, a horizontal shaft suspended beneath the car and provided at its outer end with a gear which meshes with said rack bar and at its inner end with a beveled gear, a beveled gear rotatably mounted on the lower end portion of the main shaft and meshing with the beveled gear on the horizontal shaft, a vertical governor shaft, a gear mounted on the lower end portion thereof, a corresponding gear on the main shaft, and adapted to mesh with said last named gear,

a governor device mounted on the governor shaft, and devices whereby too rapid downward movement of the car will operate the brake devices to stop said movement.

3. A safety attachment for elevator cars comprising a central vertical shaft rotatably supported beneath the car, vertical brake rails at the opposite sides of the elevator shaft, radially arranged brake devices in operative connection with said shaft and adapted to operate in connection with said vertical brake rails, devices whereby the too rapid descent of the car will throw said brake devices into operation and stop the downward movement of the car, means whereby the downward movement of the car will be stopped at a predetermined point, and supplemental stop devices whereby the downward movement of the car will be checked if the first named devices should break or fail to operate.

4. A safety attachment for elevator cars comprising a frame, a vertical threaded shaft rotatably mounted therein, vertically arranged brake rails, brake devices mounted on the threaded portion of said shaft and adapted to engage said rails, a vertical rack bar, a horizontal shaft provided with a gear which meshes with said rack bar, a gear mounted on said horizontal shaft adjacent to said vertical shaft, a corresponding gear loosely mounted on said vertical shaft and adapted to engage the gear on said horizontal shaft, a governor shaft geared in connection with the gear loosely mounted on the vertical shaft, a governor device mounted on the governor shaft, means for operating the governor in one direction only, and devices in operative connection with the vertical shaft and the governor whereby the too rapid descent of the car will operate the governor and said last named devices to rotate said shaft and operate the brake devices to stop the descent of the car.

5. A safety attachment for elevator cars, comprising vertically arranged brake rails, a vertical threaded shaft, a block movable on the threaded portion of said shaft, radially arranged brake devices the inner ends of which are connected with said block, the outer ends of said brake devices being adapted to engage said rails, a gear loosely mounted on said shaft, means for operating said gear, means for causing said gear to rotate said shaft to move said block longitudinally thereon, and means operated by the descent of the car for controlling said last named means.

6. A safety attachment for elevator cars, comprising vertically arranged brake rails, a vertical threaded shaft, a block movable on the threaded portion of said shaft, radially arranged brake devices the inner ends of which are connected with said block, the outer ends of said brake devices being

adapted to engage said rails, a gear loosely mounted on said shaft, means for causing said gear to rotate said shaft, and move said block longitudinally thereof to move said 5 brake devices into operation, and means operated by the descent of the car for controlling said last named means.

In testimony that I claim the foregoing

as my invention I have signed my name in presence of the subscribing witnesses this 10 27th day of August, 1915.

RICHARD WUNNING.
